United States Patent

Des. 238,803

Patented Feb. 10, 1976

238,803

SKI SKATE

Raymond V. Sessa, 34 Girard St.,
Marlboro, N.J. 07746

Filed May 9, 1974, Ser. No. 468,252

Term of patent 14 years

Int. Cl. D21—01

U.S. Cl. D34—15 AT

FIG. 1

FIG. 5

FIG. 6

FIG. 2

FIG. 3

FIG. 4

FIG. 1 is a perspective showing my new design;
 FIG. 2 is a top plan view of FIG. 1;
 FIG. 3 is a left side elevational view of FIG. 2, with
 the right side being substantially a mirror image thereof;
 FIG. 4 is a bottom plan view thereof;
 FIG. 5 is a front elevational view thereof; and
 FIG. 6 is a rear elevational view thereof.
 I claim:
 The ornamental design for a ski skate, substantially as
 shown and described.
